UNITED STATES PATENT OFFICE.

FRANK. BURNS, OF WESTFIELD, NEW YORK.

BOTTLE STOPPER AND FASTENER.

SPECIFICATION forming part of Letters Patent No. 289,215, dated November 27, 1883.

Application filed September 29, 1883. (No model.)

To all whom it may concern:

Be it known that I, FRANK. BURNS, a citizen of the United States, residing at Westfield, in the county of Chautauqua and State of New 5 York, have invented certain new and useful Improvements in Bottle Stoppers and Fasteners; and I do hereby declare that the following is a full, clear, and exact description of the same, reference being had to the annexed drawings, making a part of this specification, and to the letters and figures of reference marked thereon.

Figures 1 and 2 of the drawings are perspective views, showing the application of my 15 invention; Fig. 3, a detail view of the body portion of a double stopper; Fig. 4, a detail sectional view of the rubber tip. Fig. 5 is a perspective view, showing the lever forced up against the nose of the bottle and the stopper removed from the mouth of the bottle.

The present invention has relation to bottle-stoppers and stopper-fastenings; and it consists in the several details of construction, substantially as shown in the drawings, and 25 hereinafter described and claimed.

In the drawings, A represents the lever of my improved fastener, having its form substantially like that of a **W**, its ends *a* adapted to be pivotally secured to a wire around the 30 bottle's neck, or have their bearing in depressions formed in the sides of said bottle.

To eyes *b* of this **W**-shaped lever A is pivotally connected a bail, B, which passes through an opening, *c*, in or about the center 35 of a stopper, C, and is so bent as to form shoulders *d*, as shown in Figs. 1 and 2, to prevent lateral displacement of said stopper. This stopper C is formed of a body of metal, wood, or other non-elastic material in such a 40 manner as to have a hub, *e*, from which projects in a vertical direction lugs *f*, having shoulders *g*, adapted to receive and hold thereon suitable rubber tips, thereby forming a double reversible stopper. The rubber 45 tips employed upon the projections *f* of this stopper are formed with a flange, *h*, and a circular shoulder, *i*, projecting above said flange, so that when the stopper is in position for closing and the lever A brought 50 down upon the bottle this shoulder is so compressed as to admit of the hub portion *e* of said stopper being forced tightly down upon the flange, to effectually seal the bottle, and increase the power and durability of the stop-

per. When the **W**-shaped lever is forced 55 upward, to uncork the bottle, as shown in Fig. 5, the central portion of said lever will abut against the bottle's nose *k*, which will prevent the lever from swinging over on the opposite side thereof, while at the same time 60 the bail and stopper are also held on the same side with the lever by the lower end of said stopper striking against the interior of the bottle's mouth. The bail B, being pivotally connected to the lever A, swings free from 65 the bottle when the same is unclosed, carrying with it the stopper C.

The stopper, being constructed as above described and being pivotally connected to the bail on the line of its axis, will always 70 present one or the other of its ends directly to the mouth of the bottle when it is desired to close the same.

The advantages in providing a stopper with a rubber tip at both its extremities, and pivotally connecting it to the usual swinging bail, 75 is that not only can either end be used, but when one of the tips becomes worn or lost, the stopper is still capable of use by bringing the opposite end thereof to the bottle's mouth, 80 thereby rendering the stopper effective for longer use.

Having now fully described my invention, 85 what I claim as new, and desire to secure by Letters Patent, is—

1. The combination, with a suitable fastening device, of a reversible bottle-stopper pivoted thereto, and consisting of a body of wood, metal, or other non-elastic material, provided at both ends or extremities with 90 elastic tips, substantially as and for the purpose specified.

2. The combination, with a **W**-shaped lever pivoted to the bottle, and a bail pivoted to the lever, of a reversible bottle-stopper pivoted to said bail, and consisting of a non-elastic body composed of a central hub, and lugs projecting from each side thereof and provided with elastic tips, substantially 95 as and for the purpose set forth.

In testimony that I claim the above I have hereunto subscribed my name in the presence of two witnesses.

FRANK. BURNS.
